UNITED STATES PATENT OFFICE

ALBERT RUSH, OF COLUMBUS, OHIO, ASSIGNOR TO THE KINNEAR MANUFACTURING COMPANY, OF COLUMBUS, OHIO, A CORPORATION OF OHIO

DOOR FOR HANGARS AND OTHER STRUCTURES

Application filed November 12, 1927. Serial No. 232,775.

Owing to the horizontal spread of the planes or wings of a flying machine or the enormous size of a dirigible balloon a hangar or other housing for such a device must have 5 a very wide entrance, and because of such width it does not appear to be economically practical to provide such an entrance with a single rolling steel door. A steel rolling door should have vertical guiding and retaining channels for its edges, hence if a plurality of doors is to be provided for the entrance of a hangar there is presented the problem of displacing such guiding channels or posts containing one or more of them when 10 the entrance is to be opened. The present invention, therefore, has for its principal object the solution of such problem. The invention also has for its object the solution of such other problems as will hereinafter appear and 15 as may be collateral to the principal problem.

The invention is embodied in the examples herein shown and described, the features of novelty being finally claimed.

In the accompanying drawing—

25 Figure 1 is a view in elevation of the entrance end of a hangar equipped with the invention.

Fig. 2 is a combined vertical section and elevation, broken out horizontally and looking 30 toward the channel-side of one of the posts.

Fig. 3 is front view looking to the left, at the parts of Fig. 2, the clutch for operating the door being disengaged.

Fig. 4 is a somewhat similar view with the 35 trolley frame broken out to better illustrate details.

Fig. 5 is an edge view on a larger scale and with a part in section looking toward the channel side of a post showing hand-worked 40 means for operating the door.

Fig. 6 is a detail section on line VI of Fig. 5 showing means for moving one of the clutch members shown in Fig. 5 into and out of engagement with the other clutch member.

45 Fig. 7 is a front view of the post shown in Fig. 5 with the clutch members engaged and the operating crank removed.

Fig. 8 is a view like that shown in Fig. 2 with electrically operated means for working 50 the door.

Fig. 9 is a front view of the post as constructed in Fig. 8.

Fig. 10 is a detail edge view of the post showing the circuit extending means removed.

Fig. 11 is a similar view showing the circuit extending means applied.

Fig. 12 is an end elevation of the circuit extending means looking to the right as seen in Fig. 11.

In the views the character 15 designates the building with the entrance thereto at 16. Installed upon the front wall above the entrance is a plurality of flexible steel rolling doors 70 covered with hoods 17, 17^a and 17^b, the rolling doors being of the usual construction with winding shafts 12 and end brackets 13. These rolling doors are preferably counterbalanced, as usual in that type, so that each of them can be easily unrolled and rolled up 70 and remain in rolled up condition when the means for performing these operations is removed.

Mounted on the wall of the building above the hoods of the rolling doors are suitable 75 brackets 18 to the lower faces of which are secured strips 19 provided with trolley tracks 20, 20, extending parallel to the tops of the hoods. 21 designates a stout frame of reversed C-form, roughly, as viewed in Fig. 2, 80 secured to the lower arm of which is secured a post 23 having curtain guiding and retaining channels 24 at its opposite vertical sides to receive and guide the adjacent edges and margins of two of the doors or curtains. Only the intermediate posts require two door guiding channels and only one of the end or stationary corner posts requires curtain operating means. The upper arm of the frame 21 is 85 equipped with suitable trolleys 25 that engage the tracks 20, 20, said tracks and trolleys supporting the frame 21, the post 23 and the parts attached thereto, and permitting the horizontal movement of said parts across the entrance of the building.

Referring now more particularly to Figs. 2-7, inclusive, the roller or winding arbor of the flexible door has at one end a large spur gear 26 permanently engaged by a spur gear pinion 27, the shaft of which is pro-

vided with a bevel pinion 28 engaged by a bevel pinion 29 on the upper end of a shaft supported in a bracket 30 on the main end bracket of the rolling door, the lower end of said last named shaft having a clutch member 31.

On the face of the post is journaled vertically a shaft composed of two parts 32 and 33. Pinned to the upper end of the upper shaft part 32 is a clutch member 34 while the lower end enters an axial opening in an externally threaded member 35 that is pinned to the upper end of the shaft part 33. The said threaded member 35 is slit longitudinally at 35^a between its ends, the shaft part 32 therein being provided with a cross pin 32^a entering the slits 35^a to cause the clutch 34 to turn when the threaded member 35 is turned by the shaft part 33. On the lower end of the shaft 32 is a sleeve 36 threaded internally to engage the threads of the member 35, said sleeve 36 having at its upper end a hand wheel whereby it may be turned. The shaft part 32 is provided with a thrust collar 14 pinned to it, hence when the sleeve 36 is turned in one direction the clutch member 34 is raised to engage the clutch member 31; and when turned in the opposite direction permits the clutch member 34 to drop away from the clutch member 31. The cross pin 32^a makes a sliding coupling between the shaft parts 32 and 33 while the threaded members permit extension and contraction of the clutch working shaft parts. The shaft 32 has pinned to its lower end a bevel gear 37 engaged by a bevel gear 38 having a shaft 39 provided with a squared end 39^a to receive a removable crank arm 40 for turning in the desired direction the two parts together with the clutch members when coupled and the large gear of the door winding shaft to wind up or unwind and lower the flexible door. The bracket or housing 44 in which the bevel gears 37 and 38 are contained can be provided with a hasp 42 hinged thereto, said hasp provided with a cover 42^a to fit over the squared crank-receiving end of the shaft when the hasp is turned up to position for the purpose and locked upon a "staple" 43 to prevent unauthorized operation of the doors. The posts are provided at their lower ends with suitable sliding bolts 45 to engage sockets in the floor or sill to prevent swaying of the doors and posts when subjected to heavy wind pressure.

In Fig. 1 one of the doors is shown as closed, with one of the intermediate posts in position to permit operation of the rolling door. To operate such door to raise the same it is only necessary to turn the crank 40 in the proper direction to turn the clutches 31—34 and the bevel pinion 29. The door is lowered by turning the crank 40 in the opposite direction. After the door has been raised and it is desired to clear the entrance 16 the member 36 is turned to feed it down-

ward and thereby permit the clutch member 34 to drop away from clutch member 31 after which the post can be drawn on the trolley tracks toward and to the end of the opening as indicated at the right hand side of Fig. 1. 70

Referring to Figs. 8 to 10 inclusive where the power used to wind and unwind the curtain is electrical the curtain roller is shown as provided with a large bevel gear 50 engaged by a bevel pinion 51 fixed to the outer end of the shaft 52 of an ordinary electric motor 53 supported on a suitable bracket 54 secured to the inner side of the wall. The electric circuit for the motor 53 includes wires 55 that terminate in suitable spring contacts 56 in a suitable frame 57 secured to the lintel of the doorway. The circuit connecting device is carried on the inner end of a lever 58 that extends through the post 23^a and is fulcrumed on a bracket 59. The circuit connecting device has a plate 60 for carrying contacts to close with the contacts 56, and its position for connecting and extending the circuits is controlled manually by a chain 61 that passes through a flexing member 62 and a chain detaining device at 63 to hold the circuit closer up in circuit extending position when the electric motor is to be operated. When the post is to be moved horizontally after the curtain has been raised the chain 61 is removed from the detaining device at 63 and the closer allowed to drop by gravity from its circuit extending position and so left until the post is to be replaced for the closing of the curtain or door at which time the plate 60 is again raised by drawing down the chain 61 and latching it as before described. The wires from the plate 60 are extended through a tube 64 on the front of the post to a box containing three spring push buttons 65, 65^a and 65^b for the purpose of operating the motor in direct or reverse to raise or lower the curtain and to stop the motor and curtain at any point desired. The plate 60 is provided with a wedge-shaped guiding portion 66 that enters a socket in the base of the structure carrying the contacts 56. 100

While I have shown and described the invention as applied to buildings for receiving aerial vehicles it will be understood that the invention can be used in connection with any structure where it is desirable to close a wide opening or to remove a channel carrying post. 115

The forms of the parts can be changed without departing from the gist of the invention as claimed.

What I claim is:

1. In combination with a structure provided with a plurality of rolling doors, brackets supporting the doors, means for operating the doors including a clutch member, a post 125 having a guide for a margin of one of said doors, means for supporting said post permitting it to be slid laterally into and out of margin-guiding position, said post having a clutch member for cooperation with the 130

first mentioned clutch member, and means on the post for operating said clutch member and causing the operation of the door.

2. In combination with a structure provided with a plurality of doors or curtains, a post having a guide for a margin of one of said curtains, means for supporting said post permitting it to be slid laterally into and out of margin guiding position, and means carried by the post for causing the operation of said curtain, said means including a shaft carrying a clutch member to engage a clutch member operatively connected with the curtain and means for turning said shaft.

15 3. In combination with a structure provided with a plurality of doors or curtains, a post having a guide for a margin of one of said curtains, means for supporting said post permitting it to be slid laterally into and out of margin-guiding position and means carried by the post for causing the operation of said curtain, said means including an extensible shaft carrying a clutch member to engage a clutch member operatively connected with the curtain and means for turning said shaft.

4. In combination with a structure provided with a plurality of doors or curtains, a post having a guide for a margin of one of said curtains, means for supporting said post permitting it to be slid laterally into and out of margin-guiding position and means carried by the post for causing the operation of said curtain, said means including an extensible shaft carrying a clutch member to engage a clutch member operatively connected with the curtain and means for turning said shaft, said extensible shaft composed of two parts with threaded means connecting them.

30 5. In combination with a structure provided with a plurality of doors or curtains, a post having a guide for a margin of one of said curtains, means for supporting said post permitting it to be slid laterally into and out of margin-guiding position and means carried by the post for causing the operation of said curtains, said means including an extensible shaft carrying a clutch member to engage a clutch member operatively connected with the curtain and means for turning said shaft, said extensible shaft composed of two parts with threaded means connecting them and means for causing the two shaft parts to turn together.

ALBERT RUSH.
